UNITED STATES PATENT OFFICE.

JOHN DAVIDSON, OF TUTBURY, BURTON-ON-TRENT, ENGLAND.

INTERNAL-COMBUSTION ENGINE.

Application filed April 28, 1921. Serial No. 465,214.

(GRANTED UNDER THE PROVISIONS OF THE ACT OF MARCH 3, 1921, 41 STAT. L., 1313.)

To all whom it may concern:

Be it known that I, JOHN DAVIDSON, a British subject, residing at "The Elms," Tutbury, Burton-on-Trent, in the county of 5 Lancaster, England, have invented new and useful Improvements in Internal-Combustion Engines, of which the following is a specification.

This invention relates generally to that 10 type of internal combustion engines which have one or more sets of working pistons adapted to reciprocate simultaneously in the same direction, each set being connected with a charging piston, and is more particularly applicable to engines such as described in my British specification 119,414 of 1918.

The object of said invention is to build 20 engines of the specified type which will run more efficiently than hitherto and to render same simpler in construction than has hitherto been the case.

According to my invention I employ for 25 charging purposes the inner or in the case of vertical engines, the under side of the charging piston, instead of the outer or upper side as described in British specification 119,414 and provide a delivery port or ports between the inner or under side of the charging cylinder and the working chamber.

I attain this object by the means illustrated in the accompanying two sheets of drawings, in which—

Figure 1 is a side view of a vertical engine, part of which is in vertical section.

Figure 2 is a detached horizontal section on line 2—2 of Figure 1 and

Figure 3 is a detached horizontal section on line 3—3 of Figure 1.

Figure 4, is a front view in vertical section of another vertical engine.

Figure 5 is a part-sectional side view of the same.

Figures 6, 7 and 8 are detached horizontal sections on lines 6—6, 7—7 and 8—8 respectively of Figure 4.

Like numerals refer to same parts throughout the several views.

Referring to Figures 1 to 3 of the drawings, in one construction in accordance with

my invention as applied to a vertical engine, the charging piston 1 has formed with it on the under or inner side a tubular portion 2 to which is attached the connecting rod 3 in the usual way.

The tubular portion 2 is arranged to work 55 in a guide 4 provided at the lower or inner end of the charging cylinder 5, and consequently the guide 4 and tubular portion 2 cut off the lower or inner end of the charging cylinder 5 entirely from the crank 60 chamber 6 of the engine.

With a view to preventing unnecessary compression of air taking place, and at the same time with a view to maintaining as near as possible a constant pressure within the 65 crank chamber 6 of the engine, the upper side of the charging piston 1 is preferably placed in communication with the crank chamber 6 by suitable means. One suitable means consists of a port or hole 23 formed in the 70 top 7 of the charging piston in such a manner that communication is effected with the crank chamber 6, through the extended tubular portion 2 on the bottom of the charging piston.

A port 8 is provided in the charging cylinder 5 and connected up to the fuel supply, for example to a carburetter 8^a. This port may be situated about half way between the ends of the charging cylinder 5. A port 9 is also provided in the charging cylinder approximately at the bottom thereof. The port 9 is connected by a passage 10 to the inlet chamber 11 containing the inlet ports 12 of the working cylinders 13. Exhaust 85 takes place in the usual manner through the ports 14, whilst cooling water may be circulated by means of the outlet 16 and inlet 15.

In operation on the upward stroke of the working pistons to compress a charge in the working cylinders, a partial vacuum is produced in the lower part of the charging cylinder with the result that a working charge is drawn into the same when the charging piston has uncovered the port 8. 90 On ignition of the compressed charge in the working cylinders 13, the working and charging pistons perform their downward

stroke and the working charge drawn into the lower part of the charging cylinder is forced through the port 9 and passage 10 into the chamber 11. On completion of the 5 down stroke, the inlet ports 12 and exhaust ports 14 are uncovered by the working pistons and the charge in the chamber 11 enters the working cylinders 13. The next up or compression stroke now commences and the 10 inlet ports 12 are again shut off by the working pistons, whereby a partial vacuum is again produced in the lower part of the charging cylinders and the hereinbefore described operations repeat themselves.

15 It will be appreciated that as the compression in the charging cylinder takes place in accordance with my invention on the downward or inner stroke, the charge is compressed at the right time for charging.

20 The engine described is of the valveless type, the charging piston being of such a length that it only uncovers the port 8 towards the end of its outward or upward stroke.

25 The charging pump, however, may be fitted with a piston valve driven from the crank shaft, and as illustrated by way of example in Figures 4 to 8 of the drawings. This valve enables the charging pump to 30 work at higher efficiency, but for the smallest size of engines it may be dispensed with.

In the engine illustrated in Figures 4 to 35 8, the charging piston 1 has a tubular extension 2 working in a tubular guide 4 and connected to the connecting rod 3 as in the hereinbefore described construction.

A valve casing 17 is provided connected by a port 18, see particularly Figures 5 and 6, to the lower end of the charging cylinder 40 5. An inlet 19 is provided for the entrance of the working charge to the casing 17, and the casing is connected by a port 20 and passage 21 to the distributing chamber 11 for the inlet ports 12 of the working cylinder 13.

45 A piston valve 22 is reciprocated in the casing 17 for example by means of an eccentric on the crank shaft of the engine, the cycle of operations being as follows:—

50 During the up or compression stroke of the engine, the valve 22 connects the inlet 19 with the port 18 and a working charge is drawn by the charging piston 1 into the charging cylinder through the port 18.

55 During the down or working stroke of the pistons, the valve connects the port 18 with the passage 21 and the working charge is forced by the piston 1 through the port 18 into the passage 21 and chamber 11, from 60 whence it enters the working cylinders 13 as soon as the working pistons uncover the inlet ports 12 at the end of their working stroke.

In Figure 8 holes 23 are shown in the top 65 7 of the charging piston to connect the upper

side of the charging piston with the crank chamber and thereby avoid unnecessary compression in the crank chamber.

It is not intended to confine my invention to engines of the single crank type, and it can be utilized for multi-cylinder engines quite satisfactorily, as each unit is complete in itself.

The working pistons may be fitted with two sets of rings and three or four working 75 pistons may be used in connection with one charging pump piston.

I claim:—

1. In an internal combustion engine of the specified type, working cylinders; a crank chamber; a charging cylinder between the working cylinders and the crank chamber; working pistons in the working cylinders; a charging piston in the charging cylinder rigidly connected to said working pistons; a tubular extension on said charging cylinder; a stationary tubular guide embracing said extension; a port in that end of the charging cylinder which is situated nearest the crank chamber; inlet and exhaust ports in the 90 working cylinders; and a passage between the port in the charging cylinder and said inlet ports adapted to convey combustible mixture from the said end of the charging cylinder to the working cylinders. 95

2. In an internal combustion engine of the specified type; working cylinders; a charging cylinder; charging piston therein; a crank case connected to said charging cylinder; a tubular extension on said charging piston; a stationary tubular guide embracing said extension and cooperating with said extension to cut off the interior of the charging cylinder from the crank case; a port provided in the charging cylinder; a piston valve controlling the entrance and exit of a working charge through said port; and a passage connecting said port to the working cylinders. 100 105

3. In an internal combustion engine of the specified kind, working cylinders; a charging cylinder forming a continuation of the working cylinders; working pistons in said cylinders; a charging piston in said charging cylinder and rigidly connected to said working pistons in spaced relation thereto; a crank chamber on said charging cylinder; an extension on the working piston communicating with the crank case; an opening in the charging piston connecting the space between the working pistons and charging piston to the interior of the crank case. 110 115 120

4. In an internal combustion engine of the specified type, working cylinders; a charging cylinder; charging piston therein; a crank case connected to said charging cylinder; a tubular extension on said charging piston; a stationary tubular guide embracing said extension and cooperating 125 130

with said extension to cut off the interior of the charging cylinder from the crank case; a port provided in the charging cylinder; a piston valve controlling the entrance and exit of a working charge through said port; and a passage connecting said port to the working cylinders.

Signed at Manchester, in the county of Lancaster, England this 7th day of April, 1921.

JOHN DAVIDSON.
